SINGLE SIDE BAND TRANSMISSION

Ellison S. Purington, Gloucester, Mass., assignor
to John Hays Hammond, Jr.

Application September 6, 1930, Serial No. 480,166

8 Claims. (Cl. 250—10)

The present invention relates to the production and radiation of single side band transmission of radio telephonic signals or transmission of telephonic signals by a single side band in combination with a carrier.

It also relates to an improved method of producing two phase audio frequency currents for use in such radio telephonic communication, and also for other purposes.

10 An object of this invention is to reduce interference by lessening the band necessary for transmission of a given number of radio signals.

Another object of this invention is to produce 15 two currents of the same audio frequency and signal strength at a predetermined phase displacement regardless of the frequency.

Still another object of this invention is to reduce the band width required for transmission of intelligence, thereby increasing the number of 20 channels possible for communication.

A further object is the minimizing of fading effects, by permitting the carrier wave at the receiver to be demodulated with one side band only.

A still further object is the minimizing of fading by providing constant signal strength of the 25 carrier at the receiver.

An additional object of this invention is the improvement of transmission efficiency whereby the radiated power required for communication 30 may be lessened.

Another object is the improvement of efficiency of signaling by eliminating carrier frequency from the transmitter, thereby permitting higher strength of side bands representative of the signal 35 being conveyed.

Still a further object of this invention is to produce two currents of the same audio frequency and signal strength at a predetermined phase displacement for each constituent frequency regardless of the frequency.

A further object is the improvement of quality of transmission by eliminating the undesired currents produced by beating of one side band with the other side band.

45 Other objects and uses of this invention will appear from the following description taken in connection with the accompanying drawings.

The transmission of signals by use of carrier and single side band is an effective substitute for the usual carrier with both side bands, which results in lessened fading effects, less band width required for transmission, and lessened danger of interference between channels. The transmission by single side band only requires a current 50 of correct frequency to be added at the receiver,

and is especially useful for installations in which high signaling efficiency and high degree of inherent freedom from fading are desirable.

The process of single side band production involves: first, producing a two phase modulating current; second, producing a two phase current to be modulated; third, modulating one high frequency phase with one low frequency phase and the other high frequency phase by the other low frequency phase by push-pull methods; and, 10 fourth, combining the resulting modulated currents additively or subtractively to give a single side band either higher or lower than the carrier wave.

For transmission of a carrier and a single side band, the process is the same except that the carrier is also transmitted by adding carrier energy at some part of the process.

In the process of producing two phase audio current an original single phase audio current, 15 as produced in the usual microphone pick-up and amplifier circuit, is converted to a high frequency single side band by push-pull modulation and filtering out the undesired frequencies. A two phase current of the carrier frequency used in 20 the push-pull modulation is produced, and half the energy of the single side band is combined with current of one phase, and the other half is combined with current of the other phase. The resulting wave forms are separately demodulated, 25 producing two audio bands of the same strengths 30 for each frequency component, but with quadrature phase difference.

Carrier and one side band are all that are required for good transmission. Inclusion of the 35 other side band increases the signal conveyed, but requires additional band width. When the medium between transmitter and receiver operates abnormally, often there is interference between the effect of carrier and one side band and 40 the effect of carrier and the other side band, resulting in bad distortion. Also, the effect of one side band and the other side band produces distortion under perfect transmission conditions.

There is some loss of transmission efficiency 45 caused by discarding one side band, which may be made up in part by increasing the energy of the side band that is transmitted. But in general, it is fairly well conceded that carrier and single side band is superior to the usual method. 50

Single side band transmission requires the use of a local oscillator at the receiver, and the intensity of locally supplied heterodyne at the receiver may be several times that which could have been transmitted. This fact, combined with 55

the larger amount of energy which can be emitted in a side band if the carrier is omitted greatly increases the transmission efficiency. Further, single side band transmission is even more free 5 from fading than carrier and single side band transmission, because the carrier at least may be made steady at the receiver. As an alternative, the carrier may be made to increase or decrease in accordance with decreases or increases of received side band energy to maintain signal 10 strength further constant. Further, with single side band only, no sustained heterodyne tones are produced, which is perhaps the worst source of interference produced between two transmitting 15 stations on the same channel.

It is to be understood that the carrier and single side band transmission may be used with the usual type receivers, but the single side band system requires special receiving equipment.

20 With regard to interference, it is quite evident that the side frequencies of one transmission must be spaced from the side frequencies of another transmission to permit selection in reception. It is also evident that when both side 25 frequencies are transmitted the spacing of carrier frequencies for a plurality of transmissions is necessarily about twice the maximum audio frequency to be expected. With one side band eliminated, a single carrier could be utilized to 30 transmit two audio frequency signals or a single side band could be transmitted with each of two carriers spaced half the distance normally required. In this case the tuning would be to some point between the carrier and the extreme limit 35 of the side frequency band.

Heretofore the principal difficulty in eliminating one of the side bands transmitted has been that a filter which is broad enough to cover without substantial diminution of transmission over 40 the entire band of frequencies necessary, a range of say 10 kilocycles, would not exclude transmission of a portion of the other side band which would be located considerably less than 1 kilocycle from the low frequencies involved in the 45 other side band of the transmission.

It is the object of this invention to provide for a system for eliminating completely one of the side frequencies which would otherwise be radiated, by neutralizing the undesired side frequency 50 components by production of this side frequency component over two systems in phase opposition, however, simultaneously producing the desired side band components over the two systems in phase. This prevents then the necessity 55 of filtering out the undesired side frequencies as they are never produced. All filters used operate at frequencies such that filter design for proper cut-off is easily made, with no loss of tonal qualities.

60 Having thus briefly described my invention, attention is invited to the accompanying figures in which;

Fig. 1 is a diagram of a circuit which is adapted to produce two phase currents of audio frequencies;

Fig. 2 is a circuit for modulating a two phase carrier frequency by the two phase audio frequency currents produced by the circuit of Fig. 1, and thus producing and transmitting a single side band or a single side band and the carrier frequency.

Referring now more particularly to Fig. 1, which shows a circuit for producing two audio 75 frequency currents at phase quadrature, the audio

frequency current from which the two phase current is to be produced is supplied through terminals 1 and 2 and a high frequency auxiliary current is supplied by source 3. The audio frequency current is impressed upon the grid of push-pull modulator devices 4 and 5.

The auxiliary current is amplified by the device 6 and impressed into a closed circuit including inductance 7, condenser 8, inductance 9 and resistor 10 shunted by the condenser 11.

The inductance 7 is coupled to the plate circuit of the push-pull modulator 4-5, and is thus adapted to impress the high frequency auxiliary current upon the resistors 12 and 13 included in this plate circuit. The operation of the devices 15 4 and 5 as push-pull modulators is described in my copending application, Serial No. 365,222, filed May 18, 1929. In this application is also described the details of the use of condensers 15, 16, 17 and 18 in obtaining perfect elimination of 20 the high frequency output of the push-pull modulator.

The resistor 19 and filter 20 are so proportioned as to eliminate the lower side band produced by the push-pull modulation leaving energy of the 25 upper side band which later is impressed upon the grids of devices 22 and 23 in parallel.

Inductance 9 and resistor 10, shunted by the high impedance condenser 11, are so chosen as to make the voltage drop across 9 equal to, but 30 in phase quadrature with, the voltage drop across the resistor 10. Thus a two phase voltage is impressed upon the grids of the tubes 24 and 25 respectively.

The four tubes, 22, 24, 23, and 25 are so polarized that they exhibit plate rectification wherefore audio tone currents will exist across the resistors 26 and 27 included in the plate circuit of each of these devices respectively. But, because 40 of the differences of phase of the grid voltages of 24 and 25, the beat current produced in resistor 26 will be in phase quadrature to that produced in resistor 27. The output currents of the detection process are filtered by the filter networks 28 and 29 which are of the same design and are 45 adapted to eliminate the auxiliary frequency current components and other stray frequencies from their outputs.

With similar characteristics for the tubes, resistors, and filters, the final output across 30-31 is 50 equal to, but in phase quadrature with that existing across 30-32 for each frequency present in the original audio source impressed across the terminals 1 and 2. Further, because of the resistance type couplings of the modulators and de-modulators, and because the auxiliary frequency of source 3 is not much higher than the highest audio frequency, so that efficient filtering may be used, the intensity of each output frequency constituent is substantially proportional to the intensity of each input frequency constituent.

Referring now particularly to Fig. 2, this figure shows a circuit for producing a single side band transmission, or transmission of a carrier frequency current and a single side band. The terminals 30-32 are used for energizing the grid circuits of the tubes 33 and 34 which comprise a push-pull modulator arrangement, and the terminals 30-31 are used to supply the grids of tubes 35 and 36 which comprise a second push-pull modulator circuit.

The details of the two modulator circuits are similar to those of Fig. 1 and will not be again described here. The plate circuits of the two 75

push-pull modulators have impressed thereon the high frequency carrier supplied by the high frequency source 37, the output of which is so arranged as to deliver the high frequency current to the two push-pull modulator circuits at phase quadrature by means of the phase splitting circuit as shown.

The inductance resistance and capacity values of the two branches of the phase splitter are not equal but are so chosen as to make the current through one branch lead the impressed voltage by 45°, and the other lag by 45° giving 90° displacement of primary currents of the transformers.

15 The output of the tubes 33 and 34, consisting of an upper and lower side band, but no carrier frequency current, is impressed through the filter which serves to remove any audio frequency components upon the grid of amplifier 38. Similarly, the output of the modulators 35 and 36 is impressed upon the grid circuit of the amplifier device 39.

Common to the outputs of the amplifiers 38 and 39 is the resistor 41 which serves to combine the outputs of these amplifiers and impress the combined voltages upon the grid of the amplifier device 44.

Voltage of the high carrier frequency, as produced at 37, is supplied to a combining tube 40 which also has a common plate circuit with the devices 38 and 39. Each of these last mentioned devices is biased for amplification with a minimum distortion.

A short circuit switch 43 is included in the input of the device 40 and serves to control the supply of carrier current to this device, and thus, the radiation of the carrier frequency current.

The current flowing through resistor 41 serves to supply the grid of amplifier with the current components to be amplified. The current thus amplified by 44 is emitted from the antenna 45 in the usual manner.

A reversing switch 42 is included in the input of the push-pull modulator 35-36 for the purpose of reversing the direction of flow of current upon the grids of 35 and 36.

Mathematical proof of the operation of Fig. 1 is as follows:

Represent mathematically the single upper side band as produced by the push-pull modulator 4-5.

$$i_1 = \Sigma P \cos [(r+p)t + \phi]$$

Represent the two phase auxiliary current supplied to the grids of 24 and 25 as $i_2 = \cos rt$ and $i_3 = \sin rt$ the result of the combining of these currents after filtering out the high frequency will be

$$i_4 = \Sigma P \cos (pt + \phi)$$

$$i_5 = \Sigma P \sin (pt + \phi)$$

which will be equal currents but at phase quadrature for each frequency. This then shows that the audio frequency currents supplied by outputs 32 and 30, 31 and 30 are at phase quadrature.

Mathematical proof of the operation of the circuit of Fig. 2 is as follows:

Represent mathematically the two phase speech band existing across the terminals 30, 31, 32, by two equal amplitude bands as above:

$$i_4 = \Sigma P \cos (pt + \phi)$$

$$i_5 = \Sigma P \sin (pt + \phi)$$

75 and represent a two phase carrier as supplied by

37 to the plate circuits of 33-34 and 35-36 respectively as:

$$i_6 = N \cos wt$$

$$i_7 = N \sin wt$$

By push-pull modulation, combine the currents i_4 and i_6 likewise i_5 and i_7 giving for a modulated output the following:

$$i_8 = N \cos wt \times \Sigma P \cos (pt + \phi) \quad 10$$

$$i_9 = N \sin wt \times \Sigma P \sin (pt + \phi)$$

then by addition and subtraction after filtering out the high frequencies produced by the combining:

$$(i_8 - i_9) = \Sigma P N \cos [(w+p) + \phi]$$

$$(i_8 + i_9) = \Sigma P N \cos [(w-p) + \phi]$$

which represent the equations of single side band transmission bands.

With switch 43 of circuit in Fig. 2 closed, and the same constants used for the two modulator and amplifier circuits, a side frequency existing in resistor 41 as a result of tube 38 will neutralize the plate of a like side frequency existing in the output 39, while the other side frequencies are additive in effect. Thus there will exist across the resistor 41 current representative of a single side band only. Each of the side bands as utilized depends upon the direction of the current supplied to the inputs of the modulator system, and the reversing switch 42 may be utilized to vary the input of the modulator 35-36 to cause the current produced to be representative of either the upper or lower side band.

If the carrier is also to be transmitted, the switch 43 is open so that current representative of the carrier frequency will then exist across the resistor 41.

Having thus described my invention, attention is invited to the fact that I am not to be limited to the specific form shown and described for the purpose of illustration only, but by the scope of my invention as set forth in the appended claims.

I claim:

1. Means for the production of two phase audio frequency which comprises a source of intermediate frequency energy, a source of audio frequency energy, means for modulating said intermediate energy by said audio frequency energy, means for eliminating from the result of said modulation all except one of the side bands thus produced, and means for independently detecting the audio frequency existing in said side band by each of two phases of the intermediate frequency energy, each of said independent means including two thermionic devices both biased to exhibit plate rectification, an impedance common to the plate circuit of both of said devices, and means for impressing the voltage of one of the frequencies involved upon the control element of one tube and voltage of the other frequency upon the grid of the other tube.

2. The method of producing single side band transmission which comprises producing an audio frequency current representative of the intelligence to be transmitted, generating an intermediate frequency current, push-pull modulating the said intermediate frequency current by said audio frequency current, selecting one of the side bands produced by said modulation, splitting the phase of said intermediate frequency current, demodulating the selected side band by combining with each of the phases of said intermediate frequency current.

- quency current as thus produced, thus producing a two phase audio frequency current, generating a carrier frequency, phase splitting said carrier frequency, modulating one of the phases of said carrier frequency by one of the audio frequency phases thus produced, and eliminating from the result of said modulation the carrier frequency involved, modulating the other phase of said carrier frequency by the other of the audio frequency phases, eliminating from the result of said modulation the carrier frequency, and combining the product of these two modulations, thereby eliminating one of the side bands produced by each of said modulations.
- 15 3. The method of producing single side band transmission which comprises producing an audio frequency current representative of the intelligence to be transmitted, generating an intermediate frequency current, push-pull modulating the said intermediate frequency current by said audio frequency current, selecting one of the side bands produced by said modulation, splitting the phase of said intermediate frequency current, demodulating the selected side band by combining with each of the phases of said intermediate frequency current as thus produced, thus producing a two phase audio frequency current, generating a carrier frequency, phase splitting said carrier frequency, modulating one of the phases of said carrier frequency by one of the audio frequency phases thus produced, eliminating from the result of said modulation a carrier frequency involved, modulating the other phase of said carrier frequency by the other of the audio frequency phases, eliminating from the result of said modulation the carrier frequency, combining the product of these two modulations thereby eliminating one of the side bands produced by each of said modulations, combining the carrier frequency energy with the remaining of the side bands, and transmitting the high frequency components thus produced.
- 20 4. The method of producing single side band transmission by the synthetic method which comprises producing a two phase intermediate frequency current, modulating one of the phases of said intermediate frequency current by the audio frequency to be transmitted, selecting one of the side bands thus produced, detecting said side band by each of the phases of said intermediate frequency current thus producing a two phase audio frequency current, generating a carrier frequency, phase splitting said carrier frequency, modulating one of the phases of said carrier frequency by one of the audio frequency phases thus produced, and eliminating from the result of said modulation a carrier frequency involved, modulating the other phase of said carrier frequency by the other of the audio frequency phases, eliminating from the result of said modulation the carrier frequency, combining the product of these two modulations thereby eliminating one of the side bands produced by each of said modulations, combining the carrier frequency energy with the remaining of the side bands, and transmitting the high frequency components thus produced.
- 25 5. The method of producing single side band transmission by the synthetic method which comprises producing a two phase intermediate frequency current, modulating one of the phases of said intermediate frequency current by the audio frequency to be transmitted, selecting one of the side bands thus produced, detecting said side band by each of the phases of said intermediate frequency current thus producing a two phase audio frequency current, generating a carrier frequency, phase splitting said carrier frequency, modulating one of the phases of said carrier frequency by one of the audio frequency phases thus produced, and eliminating from the result of said modulation a carrier frequency involved, modulating the other phase of said carrier frequency by the other of the audio frequency phases, eliminating from the result of said modulation the carrier frequency, combining the product of these two modulations thereby eliminating one of the side bands produced by each of said modulations, combining the carrier frequency energy with the remaining of the side bands, and transmitting the high frequency components thus produced.
- 30 6. An audio frequency phase splitter which comprises means for producing an intermediate frequency current, push-pull means for modulating said intermediate frequency current by the audio frequency current which is to be split, a filter for eliminating one of the side bands produced by said modulation, means for splitting the phase of said intermediate frequency current, push-pull means for demodulating the side band passed through said filter, each side of said means comprising two thermionic devices having a common output impedance, one of which is adapted to be supplied by one phase of the intermediate frequency current and the other of which is adapted to be supplied by the side band current, and means in connection with said impedance device for producing two phase audio frequency energy.
- 35 7. An audio frequency phase splitter which comprises means for producing an intermediate frequency current, push-pull means for modulating said intermediate frequency current by the audio frequency current which is to be split, a filter for eliminating one of the side bands produced by said modulation, means for splitting the phase of said intermediate frequency current, push-pull means for demodulating the side band passed through said filter, each side of said means comprising two thermionic devices having a common output impedance, one of which devices is adapted to be supplied by one phase of the intermediate frequency current and the other of which is adapted to be supplied by the side band current.
- 40 8. The method of producing single side band transmission which comprises producing a two phase current of the high frequency, producing a two phase source of the modulating frequency representative of the energy to be transmitted, modulating one phase of said high frequency current by one phase of the low frequency current, modulating the other phase of the high frequency current by the other phase of the low frequency current, combining the result of said modulation so that the phase of one side band will be subtractive while that of the other will be additive, and also combining the energy of the high frequency with the added side bands.
- 45 9. The method of producing single side band transmission which comprises producing a two phase current of the high frequency, producing a two phase source of the modulating frequency representative of the energy to be transmitted, modulating one phase of said high frequency current by one phase of the low frequency current, modulating the other phase of the high frequency current by the other phase of the low frequency current, combining the result of said modulation so that the phase of one side band will be subtractive while that of the other will be additive, and also combining the energy of the high frequency with the added side bands.
